UNITED STATES PATENT OFFICE.

CLAUDE VERNON TURNER, OF BARTOW, FLORIDA.

TILE FOR FURNACE GRATES OF THE CHECKERBOARD TYPE.

Application filed April 4, 1921. Serial No. 458,260.

To all whom it may concern:

Be it known that I, CLAUDE VERNON TURNER, a citizen of the United States, residing at Bartow, county of Polk, State of Florida, have invented certain new and useful Improvements in Tiles for Furnace Grates of the Checkerboard Type; and I do hereby declare the following to be a full, clear, and exact description of the invention, such as will enable others skilled in the art to which it appertains to make and use the same.

This invention relates to a grate construction of the stationary type, and particularly to a specially designed tile or brick of refractory material for such a grate, said grate being primarily intended for use in a furnace fired with crude or fuel oils or any other liquid or gaseous fuel.

In the most widely used types of oil burning furnaces, the combustion chamber and ash pit are separated by means of a checkerwork made of common fire brick, said brick being substantially rectangular in shape, set on edge, with the ends thereof supported upon horizontally disposed pipes or bars, the pipes or bars being generally arranged in pairs, and the ends of each brick overlapping one of the pipes of each pair in staggered relation throughout the grate construction, in a manner similar to the squares on a checkerboard, by which name this type of grate is commonly known.

The object of placing the brick in this manner is to distribute the air evenly over the bottom of the furnace so as to form a more intimate mixture with the atomized oil or gas and thus promote a more efficient combustion. At the same time it affords a very easy and simple way of regulating or changing the area of air opening to conform to the amount of oil consumed, it having been found that in practice the best results are obtained with from two to four square inches of air opening per horse power of boiler, depending upon how much overload it is desired to carry on the boiler.

With the construction as above described, it will be noted that in each air space there is a portion of the pipe exposed to the flame, which is very liable to become overheated and allow the pipe to sag down, causing the ultimate collapse of the grate. It will also be noted that the bricks are not held in position in either direction, that is, they can slide endwise and fall between the

pipes or they can either slide or tip over sideways, causing obvious difficulties and inherent disadvantages. Attempts have been made to hold the brick in position by adding a small wedge-shaped piece of fire clay on top of the exposed pipe at the end of each brick, but this has been found to be inefficient, as said fire clay soon becomes broken and crumbles away.

Another disadvantage of the type of grate above described will be apparent upon the starting up of furnaces of the oil burning type in the manner usually employed, at which time it becomes necessary to build a wood fire on the grate in order to raise steam enough to atomize the oil and start combustion, if no other steam is available. Under these circumstances it is almost impossible to throw wood in upon these brick in this type of furnace grate without displacing the bricks comprising said grate and thus exposing the pipes to the action of the flame and causing the whole grate to collapse into the ash pit. Workmen entering the furnace for the purpose of repairs will also displace these bricks in a similar manner.

On account of the difficulty of maintaining the checker-work made of common brick, other types of grate have been resorted to, but none gives the desired results of the true checkerboard type of grate. It is the object of this invention to overcome the various defects as above noted, which has been accomplished by a specially designed tile, whereby said tile will not only be maintained in a set position but the ends of each tile will also completely cover the supporting pipes, usually employed in this type of grate, when said tiles are arranged to form a complete grate.

In the accompanying drawings, Fig. 1 represents diagrammatically an oil burning furnace provided with the improved type of grate.

Fig. 2 is an enlarged plan view illustrating the means of assembling the tile upon the supporting pipes in overlapped relation.

Fig. 3 is a side elevation thereof and

Fig. 4 is an enlarged detail view of the specially designed tile employed.

Referring to the drawings in detail, the grate 1 comprises a series of doubly arranged parallel pipes or bars 2, mounted in a furnace 3 in any suitable manner, said furnace being preferably of the oil burning type and provided with the customary ejector nozzle

conventionally illustrated at 4. Supported upon the pipes or bars 2, in staggered overlapped relation, are a series of specially designed tiles or bricks 5 of refractory material. These bricks are preferably beveled at their opposite ends as at 6, and are placed on edge upon the pipes or bars 2, the said bricks being of sufficient length so that each end thereof will rest upon and cover the adjacent pairs of doubly arranged pipes. As hereinbefore stated, the bricks are placed in staggered and overlapped relation, as clearly shown in Fig. 2, whereby the pipes will not only be completely covered, but said bricks will support each other against any tilting action or displacement longitudinally of the pipes.

In order to anchor the bricks and prevent any endwise movement thereof during the use and operation of the grate, said bricks are constructed with a downwardly projecting intermediate portion 7 adapted to engage substantially the inner sides of the adjacent pipes. It is of course to be understood that this may be a single depending portion projecting downwardly between the supporting bars, or it may be made with two projections so placed as to accomplish the same purpose.

With the construction as above described, it will be noted that the tile will be prevented from moving endways by the portion or portions projecting downwardly between the supporting pipes or bars, and also that the ends of said tile projecting over both pipes will prevent any portion of said pipes from being exposed to the action of the flames, these ends being placed in overlapped relation also preventing said tile from turning over sideways, as hereinbefore stated.

It is also to be noted that the ends of the tile do not have to be beveled, but the beveled construction is preferred for by reason of the beveled construction, when the grate is assembled, the air openings produced will be in the form of diverging nozzles, allowing the air to enter the furnace with less velocity than if the openings were in the same cross-section from top to bottom of the grate, causing less tendency for the flame to be blown upwards against the top of the furnace.

With a grate assembled and constructed with the specific type of tile, as hereinbefore described, all of the advantages of a checkerboard grate can be obtained with none of the disadvantages inherent in the common type of checkerboard grate as heretofore constructed.

What I claim is:

1. A tile or brick for grates, the transverse width or thickness thereof being uniform from end to end of said brick, relatively long undercut bottom edge portions adapted to rest on appropriate supports to form a grate and prevent accidental endwise movements of the brick, said relatively long under-cut end portions permitting a series of bricks to be placed in side over lapping staggered relation in constructing the grate, and at the same time completely cover and protect said supports from the fire generated above said grate.

2. A tile or brick for grates of the checkerboard type, the transverse width or thickness of said brick being uniform from end to end thereof, relatively long under-cut bottom edge portions formed therein adapted to rest on appropriate supports to form a grate and prevent accidental endwise movements of the brick, said relatively long under-cut end portions being of such length as to permit a series of bricks to be placed in side over-lapping staggered relation in constructing the grate, completely covering and protecting said supports from the fire generated above said grate, without additional filling material, and at the same time providing the necessary draft between said bricks.

3. In a grate construction of the checkerboard type, the combination with a series of parallel arranged supporting members, of a series of bricks of refractory material adapted to be positioned on said supporting members in staggered relation, and means carried by the bricks for preventing the accidental displacement thereof.

4. In a grate construction of the checkerboard type, the combination with a series of doubly arranged parallel supporting pipes or the like, of a series of bricks of refractory material adapted to be positioned on said supporting pipes in staggered overlapping relation, each brick having its opposite supporting end portions undercut, forming seats for said pipes, and providing a downwardly projecting intermediate portion engaging the pipes to prevent accidental endwise movements of said brick, each undercut portion being of sufficient length to span or cover both of its adjacent supporting pipes, and thus producing the side overlapping of said bricks and preventing the tilting or turning over thereof.

In testimony whereof I affix my signature.

CLAUDE VERNON TURNER.
